UNITED STATES PATENT OFFICE

109,947

DESIGN FOR A TEXTILE FABRIC

Vallejo Gantner, Hollywood, Calif., assignor to Gantner & Mattern Company, San Francisco,
Calif., a corporation of California

Application August 3, 1937, Serial No. 70,820

Term of patent 3½ years

To all whom it may concern:

Be it known that I, Vallejo Gantner, a citizen of the United States, residing at Hollywood, county of Los Angeles, State of California, have invented a new, original, and ornamental Design for a Textile Fabric, of which the following is a specification, reference being had to the accompanying drawing, forming part thereof.

The figure shows one complete section of my new design, which design is continuous.

I claim:

The ornamental design for a textile fabric, substantially as shown.

VALLEJO GANTNER.
